ENGINE GOVERNOR

Marion Mallory, Detroit, Mich.

Application January 8, 1944, Serial No. 517,485

7 Claims. (Cl. 123—103)

This invention relates to an engine governor.

In my previous application Serial No. 473,062, filed January 21, 1943, I have shown a governor for controlling the speed of an internal combustion engine wherein the governor valve is controlled by a suction device operated by the intake passageway suction and provided with an air bleed to atmosphere controlled by a centrifugally unbalanced valve. This centrifugal governor has proved very successful in operation.

The present invention relates to a modification of my aforementioned governor and in particular is concerned with a governor wherein the governor valve will open very quickly as soon as the engine speed decreases below the governor speed and wherein the governor valve will close more rapidly when the engine reaches its governed speed to prevent overrunning of the engine beyond its governed speed.

The drawing is a vertical section partly in elevation showing my governor used with a carburetor.

My engine governor comprises the following parts: a carburetor 1 having air inlet 2, manually controlled throttle valve 3, governor housing 4 having a fuel mixture outlet 5, butterfly governor valve 6 mounted on pin 7, crank arm 8 fixed on the pin 7 and connected by link 9 with diaphragm 10 in the suction device 11. Suction device 11 is connected by means of conduit 12, passageway 13 in the distributor shaft and orifices 14 and 15 with atmosphere. Orifice 14 is controlled by centrifugally unbalanced valve 16 which is urged toward open position by tension spring 17. Suction device 11 is connected by conduits 18, 19 with the intake passageway on the engine or outlet side 5 of governor valve 6. Conduit 19 is connected by conduit 20 into venturi 21. An adjustable restriction is provided between conduits 18 and 19 in the form of an orifice 22 which is controlled by a conical needle valve 23 in housing 24. Needle valve 23 has a screw fit 25 in housing 24 so that it can be turned inwardly to restrict orifice 22 and turned outwardly to open or decrease the restriction of orifice 22.

The apparatus as thus far described is identical with that shown in my copending application Serial No. 473,062 and functions in the manner described in said copending application.

The purpose of the adjustable restriction 22, 23 is to meter the suction or vacuum impressed on diaphragm 10 through conduits 18, 19 and 20. If needle valve 23 is screwed in toward a closed position, the suction on diaphragm 10 will be lowered because orifice 14 of the centrifugal

valve mechanism will have a greater air bleeding effect on the suction device 10 the further adjusting valve 23 is turned in to restrict orifice 22. Under such condition, assuming the engine is running at its governed speed and valve 6 is partly or fully closed, governor valve 6 will open very quickly as soon as the engine speed decreases enough for centrifugal valve 16 to open orifice 14 and admit air to suction device 11. This rapid opening of governor valve 6 is desirable in some cases but if valve 23 is screwed in far enough to reduce the power of suction device 11, then governor valve 6 will close more slowly permitting the engine to overrun beyond the governed speed; for example, if the engine is idling with no load and throttle 5 is opened wide, spring 27 will pull governor valve 6 wide open and the engine will run several hundred R. P. M. over its governed speed and then settle back to its governed speed. 20 This is due to the delay in the power or vacuum built up in suction device 11.

To overcome this condition I use a vacuum operated by-pass around adjustable restriction 22, 23. This vacuum operated by-pass comprises 25 a conduit 28 running from conduit 19 to conduit 18. Conduit 28 is provided with a valve 29 backed up by compression spring 30 and normally seating on seat 31. Hence, when governor valve 6 starts to close and the vacuum increases in conduit 18, valve 29 opens thereby admitting more suction to suction device 11 which causes the valve 6 to close more rapidly. The by-pass valve 29 does not affect or slow down the opening of valve 6 because the ball valve 29 remains on its seat 31 under such conditions.

I claim:

1. A device for controlling the speed of an internal combustion engine having an intake passageway comprising a governor valve, a suction responsive device connected to said governor valve for controlling the same, a conduit connecting the suction device with the intake passageway on the engine side of said governor valve, a restriction in said conduit, a by-pass conduit around said restriction, a check valve controlling said by-pass, said check valve being responsive to the suction in the intake passageway to open as the suction is increased due to the closing of the governor valve whereby the closing of the 40 governor valve is accelerated.

2. A device for controlling the speed of an internal combustion engine having an intake passageway comprising a governor valve, a suction responsive device connected to said governor valve for controlling the same, a conduit connect-

ing the suction device with the intake passageway on the engine side of said governor valve, an adjustable restriction in said conduit, a by-pass conduit around said adjustable restriction, a check valve controlling said by-pass, said check valve being responsive to the suction in the intake passageway to open as the suction is increased due to the closing of the governor valve whereby the closing of the governor valve is accelerated.

3. The combination as claimed in claim 1 including a venturi in said intake passageway on the atmosphere side of said governor, and a conduit communicating with said venturi and with the first mentioned conduit between the by-pass conduit and the intake passageway.

4. The combination as claimed in claim 2 including a venturi in said intake passageway on the atmosphere side of said governor, and a conduit communicating with said venturi and with the first mentioned conduit between the by-pass conduit and the intake passageway.

5. A device for controlling the speed of an internal combustion engine having an intake passageway comprising a governor valve, a suction responsive device connected to said governor valve for controlling the same, a conduit connecting the suction device with the intake passageway on the engine side of said governor valve, a restriction in said conduit, a by-pass conduit around said restriction, a check valve controlling said by-pass, said check valve being responsive to the suction in the intake passageway to open as the suction is increased due to the closing of the governor valve whereby the closing of the governor valve is accelerated, an air bleed to atmosphere for said suction device, and a centrifugally unbalanced valve operated in accordance with the speed of the engine and tending to shut off said air bleed when the engine reaches its governed speed.

6. A device for controlling the speed of an internal combustion engine having an intake passageway comprising a governor valve, a suction responsive device connected to said governor valve for controlling the same, a conduit connecting the suction device with the intake passageway on the engine side of said governor valve, an adjustable restriction in said conduit, a by-pass conduit around said adjustable restriction, a check valve controlling said by-pass, said check valve being responsive to the suction in the intake passageway to open as the suction is increased due to the closing of the governor valve whereby the closing of the governor valve is accelerated, an air bleed to atmosphere for said suction device, and a centrifugally unbalanced valve operated in accordance with the speed of the engine and tending to shut off said air bleed when the engine reaches its governed speed.

7. A device for controlling the speed of an internal combustion engine having an intake passageway comprising a governor valve, a suction responsive device connected to said governor valve for controlling the same, a conduit connecting the suction device with the intake passageway on the engine side of said governor valve, a restriction in said conduit, a by-pass conduit around said restriction, a check valve controlling said by-pass, said check valve being responsive to the suction in the intake passageway to open as the suction is increased due to the closing of the governor valve whereby the closing of the governor valve is accelerated, and air bleed means to atmosphere for said suction device controlled in accordance with the speed of the engine, said air bleed to atmosphere closing whenever the engine substantially reaches its governed speed.

MARION MALLORY.
